INTERNAL-COMBUSTION ENGINE.

1,022,390.

Specification of Letters Patent.

Patented Apr. 2, 1912.

Application filed September 21, 1909. Serial No. 518,814.

To all whom it may concern:

Be it known that I, JARVIS S. JENNINGS, Jr., a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to 10 which it pertains to make and use the same, reference being had to the accompanying drawings, which form a part of this specification.

My invention relates to internal combustion engines.

An object of my improvements is to secure a uniform quality of the explosive mixture in the cylinder when the power of the engine is varied.

I have shown my improvement in connection with a two-cycle engine in the accompanying drawings, in which,

Figure 1, is a side elevation of an engine embodying my invention, partly in section. 25 Fig. 2, is a central section at right angles to the plane of Fig. 1.

Similar letters refer to similar parts.

M is the working cylinder and N the crank case of a two-cycle engine; O is the 30 working piston; P the by-pass; Q the intake port to the crank case; R the exhaust port and n the main shaft.

W is a piston dividing the interior of the cylinder M into a combustion chamber B 35 between the pistons O and W and an air chamber A between the piston W and the head of the cylinder. The piston W is provided with the usual packing rings and is adapted to move in the cylinder M and to 40 form a tight joint with the walls thereof.

D is a groove formed around the periphery of the piston W; C is a passageway in the piston W communicating with the groove D, and with the chamber A.

E¹, E², E³, E⁴, are apertures or passages 45 through the wall of the cylinder M located in different planes longitudinally of said cylinder.

G¹ is a hollow casing secured to the side 50 of the cylinder M and having passageways leading from its interior and communicating with the passages E¹, E², E³, E⁴.

G is a hollow cylinder fitting in the casing

G¹ and adapted to turn and reciprocate therein; F¹, F², F³, F⁴, are apertures through 55 the wall of the cylinder G located in different angular positions, that is to say, in different planes through the axis of said cylinder and spaced a distance apart longitudinally of the cylinder equal to the distance 60 apart of the passageways, in the casing, which communicate with E¹, E², E³, E⁴.

I is a connecting-rod pivoted eccentrically to the shaft n so as to be oscillated by the rotation of said shaft so that one of the 65 apertures F¹, F², F³, F⁴, shall communicate with a passage E¹, E², E³ or E⁴, at the lower end of the travel of the piston O. The upper end of the connecting-rod I is secured to the cylinder G by a ball and socket joint. 70

J is a handle engaging the upper end of the cylinder G by which handle said cylinder may be rotated.

K is the cylinder of a small air pump 75 secured to the cylinder M.

S is a connecting-rod, the lower end of which is pivoted eccentrically to a gear wheel s adapted to be rotated by a gear wheel upon the main shaft n of the cylinder. The piston of the air pump K is reciprocated 80 by means of the connecting-rod S in the usual way. The piston of the air pump is so connected to the moving parts of the engine that it shall supply a small quantity of air to the air chamber A during the downward movement of the piston O and so that it shall start on its suction stroke slightly before the piston W reaches its lower limit, the pump supply port being so located as 85 not to be uncovered by the piston until the suction stroke is nearly completed.

T is a pipe leading from the delivery port of the cylinder R into the chamber A above the piston W in the cylinder M.

t is an inwardly opening non-return valve 95 at the delivery end of the pipe T.

The operation of the above described device is as follows: The cylinder G is turned until one of the ports F¹, F², F³, F⁴, registers with a corresponding passage in the casing which communicates with one of the apertures E¹, E², E³, E⁴. In the operation of the engine air is intermittently supplied to the chamber A by means of the pump K, thus increasing the pressure in said chamber 100 and acting to force the piston W downward. 105

When the piston W is forced down until the groove D registers with a port E¹, E², E³, or E⁴, which is in communication with the outer air through the interior of the cylinder 5 or plug G, the surplus pressure is discharged. The connecting-rod I is so connected with the shaft n that the chamber A will be open through one of said passages at the lower end of the travel of the piston O. When 10 the piston O is in the position indicated in Fig. 2, the explosive mixture is forced into the combustion chamber B from the crank case through the by-pass P in the usual manner, expelling the residual products of combustion 15 from said chamber. As the piston O rises it compresses the charge above it, forcing the piston W upward and causing a compression of the air in the chamber A. When the explosion occurs the piston W is 20 forced still farther up being cushioned by the air above it and the shock of the explosion is lessened by the piston W yielding to its pressure. When the piston O has again descended the exhaust port R will be open 25 discharging the products of combustion in the usual way and permitting the piston W to descend under the impulse of the pressure above it until said pressure is relieved through that one of the ports E¹, E², E³, E⁴, 30 which is in communication with the outer air through the interior of the cylinder G. When the piston W has reached this position it will be prevented from falling much below it because if it did so it would close the 35 port in the cylinder M and draw a vacuum above it; moreover there would be some pressure in the combustion chamber which would act to prevent the piston W from descending farther. If there is little or no 40 throttling the cylinder G will be turned to put the upper passage E¹ into communication with the outer air; if there is a greater degree of throttling said cylinder will be turned to put the passage E² into communication 45 with the outer air; and so with still greater degrees of throttling the cylinder G will be turned to put the passage E³ or E⁴ into communication with the outer air as the case may require. When a change is made 50 of the angular position of the cylinder G so as to bring a lower passage E², E³ or E⁴ into communication with the outer air the piston W will be forced down in one or more strokes by the air supplied by the 55 pump K until said piston comes to a position in which the groove D registers with a port E², E³ or E⁴. Thus the lower position of the piston W may be adjusted by turning the cylinder G by the handle J. In this way 60 the size of the combustion chamber is adjusted to the variable quantity of the explosive mixture which may be used for each charge and thus the degree of its dilution by the residual products of combustion may 65 be made approximately uniform so that

back-firing will be obviated, increased power will be obtained from the engine and uniformity of action will be secured.

It is obvious that the means for rotating the cylinder G and bringing the various ports 70 E¹, E², E³, E⁴ in communication, as hereinbefore stated, may be connected to the means for controlling the throttle valve in the proper relation so that one movement of a lever will control both, and as these means 75 of simultaneous control are old and well known it is not deemed necessary to describe or illustrate them in detail.

What I claim is.

1. In an internal combustion engine the 80 combination of a working cylinder, a working piston in said cylinder, a free piston fitting in said cylinder between the working piston and cylinder head, adapted to be elastically variably moved longitudinally 85 therein by an excess of pressure upon one of its ends and dividing said cylinder into a combustion chamber and an air chamber, means for forcing air into said air chamber, and means for relieving the pressure in said 90 air chamber at predetermined positions of said piston.

2. In an internal combustion engine the 95 combination of a working cylinder, a working piston in said cylinder, a free piston fitting in said cylinder between the working piston and cylinder head, adapted to be variably moved longitudinally therein by an excess of pressure upon one of its ends and dividing said cylinder into a combustion 100 chamber and an air chamber, means for forcing air into said air chamber and manually controlled means for relieving the pressure in said air chamber at different predetermined positions of said piston. 105

3. The combination of the cylinder M, a piston O in said cylinder, a piston W therein, between the piston O and the head of the cylinder, dividing the interior of said cylinder into chambers A and B, means for supplying air to chamber A, a plurality of apertures through the wall of the cylinder M so located that they shall be put successively into communication with the chamber A as the piston W moves toward the piston O, 110 and a valve adapted to put one of said apertures or another into communication with the outer air, means for adjusting said valve to put the required one of said apertures into communication with the outer air and 115 means for reciprocating said valve.

4. The combination of the cylinder M, a piston O in said cylinder, a piston W therein, between the piston O and the head of the cylinder, dividing the interior of said cylinder into chambers A and B, means for supplying air to chamber A, a plurality of apertures through the wall of the cylinder M so located that they shall be put successively 125 into communication with the chamber 130

A as the piston W moves toward the piston O, and a valve adapted to put one of said apertures or another into communication with the outer air, a part of said valve being connected to the operative parts of the engine so that it may open the required one of said apertures at the required position of said operative parts.

5. In an explosive engine provided with a cylinder M, a piston O in said cylinder, a piston W in said cylinder, between the piston O and the head of the cylinder, dividing the interior of the cylinder into chambers A and B, means for supplying air to chamber A, a plurality of passages E¹, E², through the wall of said cylinder so located that they shall be put successively into communication with the chamber A as the piston W moves toward the piston O, a casing on the outside of said cylinder, a hollow cylinder adapted to turn and reciprocate in said casing, said cylinder having apertures at different angular positions adapted to be put in communication respectively with one of the passages E¹, E², and means for reciprocating the cylinder in said casing, substantially as and for the purpose described.

6. In an explosive engine provided with a cylinder M, a piston O in said cylinder, a piston W in said cylinder, between the piston O and the head of the cylinder, dividing the interior of the cylinder into chambers A and B, means for supplying air to chamber A, a plurality of passages E¹, E², through the wall of said cylinder, so located that they shall be put successively into communication with the chamber A as the piston W moves toward the piston O, a casing on the outside of said cylinder, a second cylinder adapted to turn and reciprocate in said casing, said second cylinder having apertures communicating with the outer air located at different angular positions, adapted to be put in communication respectively with one of the passages E¹, E², and a connecting rod pivoted eccentrically to the main shaft of the engine at one end and by a ball-and-socket joint with said second cylinder at the other end.

50 7. In an internal combustion engine, having a working cylinder, a working piston in said cylinder, a second piston engaging in said cylinder between the working piston and the head of said cylinder, means for supplying an elastic fluid under pressure to the chamber formed between said second piston and the cylinder head, and manually controlled means for fixing the position of the range of travel of said second piston,

the said means controlling the said second piston through said elastic fluid, substantially as described.

8. In an internal combustion engine, having a working cylinder, a working piston in said cylinder, a second piston engaging in said cylinder between the working piston and the head of said cylinder, means for supplying an elastic fluid under pressure to the chamber formed between said second piston and the cylinder head where it remains at all times exercising a substantially uniform pressure, and manually controlled means for fixing the position of the range of travel of said second piston, the said means controlling the said second piston through said elastic fluid, substantially as described.

9. In an internal combustion engine, having a working cylinder, a working piston in said cylinder, a second piston engaging between the working piston and the head of said cylinder, means for supplying an elastic fluid under pressure to the chamber formed between the said second piston and the cylinder head, and selective means for choosing one of a multiplicity of ranges of substantially equal travel of the said second piston, substantially as described.

10. In an internal combustion engine, having a working cylinder, a working piston in said cylinder, a second piston engaging in said cylinder between the working piston and the head of the cylinder, means for supplying an elastic fluid under pressure to the chamber formed between said second piston and the cylinder head, and means for varying the position of the range of travel of the said second piston by controlling the discharge of the elastic fluid from said chamber, substantially as described.

11. In an internal combustion engine having a working cylinder, a working piston in said cylinder, a second piston engaging in said cylinder between the working piston and the head of the cylinder, a cushioning element between the second piston and cylinder head having at all positions of the second piston a uniform elasticity, and means for selectively choosing the position of the range of travel of said second piston without materially altering its distance of travel when subjected to stress, substantially as described.

In testimony whereof, I sign this specification in the presence of two witnesses.
